FOREIGN PATENT DOCUMENTS

EP	2639144	9/2013
FR	2764261	12/1998

Primary Examiner — Darlington Ly*(74) Attorney, Agent, or Firm* — Norton Rose Fulbright Canada LLP(57) **CLAIM**

The ornamental design for an electric bicycle, as shown and described.

DESCRIPTION

FIG. 1 is a right rear perspective view of an electric bicycle in accordance with our new design;

FIG. 2 is a left and front perspective view thereof;

FIG. 3 is a top plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines in the drawings illustrate portions of the electric bicycle that form no part of the claimed design.
